BY Richard Oliver.

ATTORNEY

UNITED STATES PATENT OFFICE.

HARRY R. SHIFFER, OF BROWNSTOWN, PENNSYLVANIA.

RECEPTACLE.

1,263,946.

Specification of Letters Patent. Patented Apr. 23, 1918.

Application filed June 24, 1916. Serial No. 105,651.

To all whom it may concern:

Be it known that I, HARRY R. SHIFFER, a citizen of the United States, residing at Brownstown, in the county of Lancaster and State of Pennsylvania, have invented certain new and useful Improvements in Receptacles, of which the following is a specification.

This invention relates to the class of receptacles.

The invention has more especial reference to a device of the character stated, for use by confectioners and the like, where it is desirous of providing a box, which when once opened, will effectively prevent the reusing of the same, thus preventing the using of the box for placing other goods than the original contents thereof, on sale.

More particularly the present invention has reference to the construction of means whereby the closure or lid of the box will be securely held thereon, and when once broken open will as above stated, prevent the fraudulent reusing of the same.

Another important characteristic of the invention resides in the arrangement of the lid releasing means, and it may be stated that it is among the primary objects of the invention to simplify and reduce the cost of manufacturing of constructions of this character and provide novel details in the construction and arrangement of parts with a view to higher efficiency generally.

Other improvements and novel details in the construction and arrangement of parts will be appreciated from the detailed description below, which should be read in connection with the accompanying drawings forming a part hereof, and wherein I describe a preferred embodiment of the invention for the purpose of illustration.

In the drawings:

Figure 1 is a side elevation partly in section of my improved receptacle;

Fig. 2 is a top plan of the receptacle;

Fig. 3 is a bottom plan of the lid or closure therefor, and Fig. 4 is a detail inverted plan view of the box showing the seal hereinafter referred to.

Referring now to the drawings wherein like reference numerals designate like or corresponding parts throughout the several views, I employ the usual receptacle 1 having the usual cover or lid 2 therefor, the lid being provided with a finger opening 3 for an obvious purpose. Upon either side of the

receptacle 1 adjacent the end walls thereof, I arrange channeled strips 4 which are secured to the adjacent end walls through the medium of tangs 5 which are formed upon the outer edges of said strips and are passed through the end walls and bent into position as shown to advantage in Fig. 2, thus holding the channeled strips in place and preventing the displacement thereof under ordinary circumstances. Within the channeled strips 4, I position latches or hooks, the lower extremities of which are bent at substantially right angles to the body portion thereof to provide means whereby a connecting cord, which will be subsequently described, may be engaged therewith. The laterally extended portions are indicated by the numeral 7, and of course are provided with suitable openings whereby the said cord may be passed therethrough. A secondary or false bottom 8 is arranged within the receptacle 1 and provides efficient means whereby the contents of the box may be held out of engagement with the laterally extended portions of the hooks 6 and also the connecting cord.

The lid carries upon the upper portion thereof a plurality of dependent catches generally indicated by the numeral 9, the faces of which are bent at angles thereto and are formed with tangs 10 which are thrust through the top portion of the lid and bent over as shown in Fig. 1, thereby preventing the ready removal or displacement of said catches. It is to be noted that the catches 9 are so arranged as to align with the channeled strips 4 affixed to the receptacle 1, and therefore it is obvious that when the lid 2 is placed over the receptacle 1 and moved downwardly, the catches 9 will subsequently be received by the channeled strips 4, and guided thereby into engagement with the hooks 6 positioned therein.

In order to provide means whereby the lid will be held in closed position when its catch members 9 are once engaged with the hook members 6, I connect to the lateral extremities of the hooks, a cord 11 arranging this cord longitudinally of the box. An opening 12 is formed within the bottom of the receptacle 1, directly beneath the connecting cord 11, and is closed by a seal 13, shown in Fig. 4, which is applied thereover. Thus, it will be seen, that after breaking the seal 13 and severing the cord at this point, the buyer may remove the cover 2

by merely drawing the same upward, which action will cause the withdrawal of the hooks 6 from the channeled strips 4, and it will be apparent that when the cord 11 has been severed and the lid 2 removed from the receptacle 1, it will be impossible to again lock the lid on the box because of the fact that the seal has been broken and also that the securing hooks have been withdrawn from their respective channeled strips 4.

If so desired, the opening 12 may be dispensed with and a portion of the bottom 1 as adjacent the cord 11 may be perforated, thus rendering it possible for the buyer to readily remove the said part, and by so doing expose the connecting cord 11 for the severing action.

While I have herein disclosed a specific embodiment of the invention, it will be apparent to persons skilled in the art that the invention is capable of embodiment in other forms and devices differing in detail and arrangement from that shown, and as may be in keeping with the hereto appended claims.

Having thus described the invention, what is claimed is;—

1. A receptacle having a cover, said receptacle having an opening in the bottom, catches carried by said cover adjacent its ends, hooks carried by said receptacle adjacent the ends thereof, said catches engaging said hooks and a flexible connection between said hooks, said connections being severable through the opening in the bottom to release the hooks and catches and permit the removal of the cover.

2. A receptacle having an opening in the bottom, a cover positioned on said receptacle, a false bottom carried in said receptacle, channeled strips secured to said receptacle at the ends thereof, hooks located in said strips, catches carried by said cover, said catches projecting into said strips to engage said hooks, when said cover is placed on said receptacle, and a flexible connection connecting said hooks, said flexible connection being disposed beneath the false bottom and accessible through the opening, whereby the connection may be cut to permit the withdrawal of said catches and hooks from said strips in removing said cover from said receptacle.

3. A receptacle having an opening in the bottom and a cover, hooks carried by said receptacle, catches carried by said cover, said catches engaging said hooks for holding the

cover on said receptacle, and a cord connected to said hooks for holding the same in set positions, said cord being accessible through the opening, and a seal normally closing said opening.

4. A receptacle having a cover and a false bottom, said receptacle having an opening in its lower portion beneath the false bottom, channel strips at the ends of said receptacle, hooks loosely carried in said channeled strips and having portions projecting beneath the false bottom, a connection between said hooks for normally holding the hooks in place, and catches carried by the cover and engageable with said hooks, and said strips forming guides for the catches.

5. A receptacle having an opening and a cover, a false bottom in said receptacle, channeled strips at the end of said receptacle, a cord positioned beneath said false bottom and being accessible through said opening, and means carried within said channeled strips for connecting the ends of said cord to said cover for preventing the accidental displacement of said cover, and said cord being adapted to be severed adjacent said opening for permitting the removal of said cover.

6. A receptacle having an opening and a cover, a cord positioned within said receptacle, means connecting said cord to said cover, thus holding said cover against accidental displacement, said cord being accessible through said opening for allowing the cord to be severed when said cover is to be removed.

7. A receptacle having a cover and a false bottom, channel strips at the ends of the receptacle, said receptacle having an opening beneath the false bottom, hooks loosely carried in said channeled strips and having portions projecting beneath said false bottom, a connection between said hooks for normally holding the hooks in place, catches carried by the cover engageable with said hooks, said strips forming guides for said catches, said connections being accessible through said opening, and a seal carried by said receptacle and normally closing said opening.

In testimony whereof I affix my signature in presence of two witnesses.

HARRY R. SHIFFER.
